UNITED STATES PATENT OFFICE.

JOSEPH C. AYOTTE, OF BIDDEFORD, MAINE.

SHUTTLE LOCK.

Application filed February 12, 1923. Serial No. 618,651.

To all whom it may concern:

Be it known that I, JOSEPH C. AYOTTE, a citizen of the United States, residing at Biddeford, in the county of York and State of Maine, have invented certain new and useful Improvements in Shuttle Locks, of which the following is a specification.

This invention relates to checks or locks for shuttles and the primary object of the invention is to improve the construction of the said checks or locks whereby a simplified lock will be provided, which will eliminate a number of parts heretofore considered necessary in such locks and reduce wear on the loom, the shuttle, and the said shuttle lock or check.

A further object of the invention is to provide a rocking lock or check for shuttles embodying an adjustable leaf spring member carried by said check or lock, which is so constructed as to increase the tension on the said lock when the shuttle comes into engagement therewith, thereby effectively bringing the shuttle to a stop and hold the same against accidental movement thereafter.

A still further object of the invention is to provide an improved shuttle check or lock of the above character, which will be durable and efficient in use, one which will be simple and easy to manufacture, and one which can be placed upon the market at a reasonable cost.

With these and other objects in view the invention consists in the novel construction, arrangement and formation of parts, as will be hereinafter more specifically described, claimed and illustrated in the accompanying drawings, in which drawings:

Figure 1 is a plan view of the improved shuttle check or lock showing the same in use.

Figure 2 is an edge elevation of the check or lock.

Figure 3 is a detail perspective view of the tension spring.

Referring to the drawings in detail, wherein similar reference characters designate corresponding parts throughout the several views, the letter A generally indicates the improved check or lock, which has been particularly made for use with the Crompton-Knowles loom, but it is to be understood that the same can be used with other types of looms. In view of the fact that the invention resides and includes the

construction of a lock per se, the same has only been shown with the loom and a portion of a loom is of course to be of the ordinary or any preferred construction.

The improved lock A embodies the arm 5 having the arcuate extension 6 formed on one end thereof which carries the shoe 7. The shoe 7 is provided with the ordinary type of friction pad 8, which as shown is preferably made of sole leather. The opposite end of the arm 5 is provided with a barrel 9 which receives a screw bolt 10. This bolt 10 forms means for attaching the device to the box plate of the loom and it is to be understood that the lock is adapted to rock upon said bolt, the bolt being provided with suitable locking nuts 11 and 12 and spacing washers 13. If so desired the arcuate extension 6 can be provided with an outwardly extending ear 14, which can support an adjustable screw 15, which constitutes a stop for the lock and it is obvious that by adjusting the stop the swinging movement of the lock can be limited. This screw is adapted to engage the binder portion of the loom. The adjusting screw can be provided with a suitable lock nut 15 if so desired.

The tensioning means comprises a substantially heavy leaf spring 20 and this spring is preferably bowed throughout its length and is provided with an attaching portion 21 having a pair of openings 22 therethrough, through which is adapted to extend the attaching screws 23 which are threaded into the arm 5. This tensioning device is adapted to rest at a point intermediate its ends upon the barrel 9 which can be notched to receive the same. The extreme outer end of the resilient tensioning device 20 is bent back upon itself to provide a right angularly extending foot 24 which can be provided with a guide lug 25. The foot 24 and the guide lug 25 are adapted to engage the binder portion of the loom, as will be hereinafter more fully described.

In operation of the improved shuttle check or lock, when the shuttle comes to the side of the loom where the lock is attached, the same comes up against the binder and strikes the pad 8 causing a pressure on the arm 5, which rocks the arm on the barrel 9. This causes the free end of the tensioning device to press against the binder, which of course sets up a friction on the shuttle, thereby locking the shuttle against further move-

ment, so that the same becomes rigid and thus will not jump while the transfer from the empty bobbin to the full bobbin is being made.

- 6 It is obvious from the foregoing that an exceptionally simple shuttle lock has been provided embodying a minimum number of parts and which will operate in an effective and simple manner to carry out the purpose intended.

Changes in details may be made without departing from the spirit or the scope of this invention.

What I claim as new is:—

- 15 A lock for shuttles of looms comprising

ing a rocking body including an arm, a barrel formed on one end of the arm, a pivot bolt carried by said barrel, an arcuate extension formed on the opposite end of the arm, a shoe carried by said extension, a pad secured to said shoe, an arcuate resilient tensioning arm, means adjustably and detachably connecting said arm to the arm of the rocking body, and a right angularly extending foot formed on the free end of said tensioning arm.

In testimony whereof I affix my signature.

JOSEPH C. AYOTTE.
